Primary Examiner — Mark Goodwin(74) *Attorney, Agent, or Firm* — Brooks Kushman P.C.**CLAIM**

The ornamental design for a cultipacker, as shown and described.

DESCRIPTION

FIG. 1 is a perspective view of a cultipacker showing an embodiment of my new design;

FIG. 2 is a top plan view thereof;

FIG. 3 is a bottom plan view thereof;

FIG. 4 is a front view thereof;

FIG. 5 is a rear view thereof;

FIG. 6 is a left side view thereof; and,

FIG. 7 is a right side view thereof.

The broken lines are for illustrative purposes only and form no part of the claimed design.
